SPRINKLER HEAD

Vincent C. Cerasi, New York, N. Y.

Application November 20, 1952, Serial No. 321,586.

12 Claims. (Cl. 299—130)

The present invention relates to sprinklers, spray heads, nozzles and the like, herein referred to generically as "sprinkler heads."

The sprinkler heads in accordance with the invention are applicable to producing spray or water stream configurations of an ornamental or esthetic nature, as, for example, in decorative fountains. The construction in accordance with the invention makes it possible to obtain a wide variety of decorative spray configurations and to vary the configurations as desired.

The invention is also applicable to spray heads for utilitarian purposes, as, for example, sprinkling fields, lawns and gardens, sprays for cooling or condensing systems and sprays for water purification or aeration systems. Here again, the form of the spray produced by the sprinkler head in accordance with the invention may be varied to suit the particular purpose for which the sprinkler is used.

It is an object of the present invention to provide a sprinkler head that is composed of a small number of simple parts that can be economically manufactured and easily assembled, so that the overall cost of production of the sprinkler head is low.

A further object of the invention is to provide a sprinkler head that can be easily adjusted to provide a wide variety of different spray configurations. The discharge rate—at a given pressure—can likewise be varied through wide limits. A further advantage of the construction in accordance with the invention is that it is relatively free from clogging by particles in the liquid and, in the event any clogging does occur, the sprinkler head can easily and quickly be cleaned and cleared.

Further objects and advantages of the invention will be apparent from the following description and claims in accordance with the accompanying drawings which show, by way of example, preferred embodiments of the invention:

In the drawings:

Fig. 1 is a side elevation of a sprinkler head in accordance with the invention.

Fig. 2 is a cross section taken approximately on the line 2—2 in Fig. 1.

Fig. 3 is a longitudinal section of the sprinkler on a larger scale.

Fig. 4 is a view similar to Fig. 3 but showing a modification.

As illustrated in Figs. 1, 2 and 3 of the drawings, the sprinkler head in accordance with the invention comprises a central shaft 1 and a plurality of cylindrical cup-shaped members 2, 3, 4 and 5 that are screwed into the shaft 1.

The central shaft 1 is threaded throughout its length and has a plurality of longitudinal flutes or grooves 11 extending from one end of the shaft to the other. The grooves 11 are preferably about as wide as the lands 12 between the grooves and are relatively deep, having, for example, a depth greater than half the radius of the shaft. As shown in Fig. 2, the grooves have approximately parallel sides and rounded bottoms. The number of grooves is preferably small, being, for example, at least three and not more than six. When four grooves are used, as illustrated in the drawings, the shaft has a cross section something like a Maltese cross. The total cross sectional area of the grooves is preferably about equal to the cross sectional area of the solid part of the shaft. While the flutes or grooves 11 can, if

2

desired, extend spirally along the shaft, the construction is simpler if they are straight and parallel to the longitudinal axis of the shaft.

The lower cylindrical cup-shaped member 2 has a cylindrical upper skirt portion 15 the upper edge of which is beveled, as indicated at 16, so that it is disposed at an angle to the axis of the shaft 1 and conforms to a conical surface coaxial with the shaft. At the bottom of the skirt portion, an inwardly projecting annular flange portion 17 forms a restricted neck that is internally threaded and of a diameter to be screwed onto the lower end of the shaft 1 (Fig. 3). Below the flange 17, there is a lower annular skirt portion 18 that is internally threaded, as indicated at 19, so as to be screwed onto a pipe, hose, or other conduit for supplying liquid to the sprinkler head. Immediately below the inwardly projecting flange 17, there is provided an annular recess 20 that is adapted to receive a rubber washer or gasket for the purpose of making a fluid-tight joint between the sleeve member 2 and the supply conduit. After the sleeve member 2 has been screwed onto the lower end of the shaft 1, it is preferably held in place by a set screw or pin 21.

Intermediate cup-shaped members 3 and 4 are screwed onto the shaft 1 above the lower member 2. Each of the intermediate members has a cylindrical skirt portion 23 having its upper edge beveled, as indicated at 24. An annular flange 25 projects inwardly from the lower portion of the skirt 23 and is internally threaded and of a diameter to be screwed onto the shaft 1. The lower peripheral edges 26 of the intermediate members are beveled in the same direction as the upper edges of the skirt portions. It will be seen that the skirt portions 23 of the intermediate members 3 and 4, as well as the skirt portion 15 of the lower member 2, are spaced from the shaft 1 so that there is an annular space between the shaft and the respective skirt portions.

The uppermost cylindrical member 5 is shaped like an inverted cup having a skirt portion 30 that is internally threaded so as to screw on to the upper end of the shaft 1. The cap 5 has an end wall 31 which may either be imperforate or may have one or more small holes 32. Where a plurality of holes is used, the holes are preferably divergent upwardly so that jets or streams of liquid issuing from the holes diverge in a predetermined pattern. The lower peripheral edge of the skirt 30 is beveled, as indicated at 33, the direction and angle of bevel being approximately equal to that of the upper edge 24 of the adjacent member 4.

The cylindrical cup-shaped members 2, 3, 4 and 5 are separated from one another in an axial direction so as to leave annular spaces between successive members. By reason of the inclination or bevel of the facing peripheral edges of successive members, the spaces between them form annular nozzles or passageways that are inclined to the axis of the shaft. The upper edge of member 3 and facing lower edge of member 4 are disposed at a lesser angle to the axis of the shaft than the upper edge 16 of the member 2 and the facing lower edge of member 3. Likewise, the upper edge of member 4 and facing lower edge of member 5 are at a still smaller angle relative to the axis of the shaft. Inclination of the annular passageways between successive members thus varies progressively. The external diameters, as well as the internal diameters, of the members 2, 3, 4 and 5 are substantially equal so that the overall configuration of the sprinkler head is cylindrical.

Liquid entering the lower end of the lower member 2 flows upwardly through the longitudinal flutes or grooves 11 in the shaft 1 and fills the annular spaces between the shaft and the upwardly projecting skirt portions of members 2, 3 and 4. The cap 5, screwed onto the upper end of the shaft, forms a closure, or a substantial closure, for the channels formed by the grooves 11 in the shaft, so that the liquid is forced out through the annular spaces or passageways between successive members 2, 3, 4 and 5. As noted above, these passageways are preferably disposed at different angles relative to the axis of the shaft. By turning individual ones of the elements 3, 4 and 5, they can be moved axially along the shaft so as to vary the spaces between successive

members. The nature of the spray produced is accordingly varied. For example, if the space between members 2 and 3 is relatively large while the space between members 4 and 5 is closed, or relatively small, a larger proportion of liquid will be thrown out in a flat sheet or spray. Conversely, if the space between members 2 and 3 is reduced or closed and the space between members 4 and 5 is relatively large, more of the liquid will be projected upwardly at a sharper angle to the axis of the sprinkler head. Likewise, all of the spaces may be made larger or smaller to control the fineness or coarseness of the spray. The threaded bore in the cap member 5 is sufficiently long to permit the desired range of adjustment. The amount of liquid discharged through any holes 32 that may be provided in the end wall 31 of the cap member 5—at a given supply pressure—depends on the degree to which the spaces between the members 2, 3, 4 and 5 are opened or closed. Thus, if they are relatively open, less liquid will be forced out through the holes 32.

It will be understood that the number of cylindrical cup-shaped elements that are screwed onto the fluted shaft 1 may be varied as desired, the length of the shaft being varied accordingly. For example, as illustrated in Fig. 4 where corresponding parts are designated by the same reference numerals as in Figs. 1 to 3, there is a lower member 2, upper member 5 and a single intermediate member 3. Fewer or more members can be screwed onto the shaft, as desired. Thus, a variety of different sizes of sprinkler heads can be assembled from the same basic elements. The threaded fluted shaft is preferably produced in long lengths which are then cut up to the lengths desired for individual sprinkler heads. The bottom members 2 and top members 5 are the same for all sprinkler heads of a series, regardless of the number of elements used, except that the angle of bevel of the edges may be changed. Likewise, all of the intermediate cup-shaped members 3 and 4 are identical with one another except that the angle of bevel may be varied. The manufacture of the sprinkler heads is thus greatly simplified.

While preferred embodiments of the invention have been shown by way of example in the drawings, it will be understood that the invention is not limited to these embodiments but may be modified within the scope of the appended claims. It will also be understood that the terms "upper," "lower," etc., refer to the position shown in the drawing and that the sprinkler head can be used in any desired position. Likewise, the bevel of the peripheral edges can be toward the inlet, rather than away from the inlet as shown, and the angle of bend may be varied to produce the discharge pattern desired.

What I claim and desire to secure by Letters Patent is:

1. A sprinkler head comprising a shaft of uniform diameter threaded uniformly throughout its length, said shaft being fluted throughout its length with a plurality of channels extending longitudinally of the shaft, a lower cylindrical member having an upper circumferential skirt portion, an intermediate neck portion that is internally threaded and screwed on the lower end portion of said shaft and a lower circumferential skirt portion that is internally threaded for connection to a supply conduit, at least one intermediate cup-shaped member having a circumferential skirt portion and an annular inwardly projecting flange portion that is internally threaded and screwed on an intermediate portion of said shaft and an inverted cup-shaped upper member having an end wall

overlying the upper end of said shaft and a circumferential wall that is internally threaded and screwed on the upper end portion of said shaft, said members being spaced from one another along said shaft.

5. 2. A sprinkler head according to claim 1, in which the facing peripheral edge portions are beveled in the same direction to provide annular discharge passage inclined at an angle to the longitudinal axis of the nozzle.

10 3. A sprinkler head according to claim 2, in which the angle of one of said passages to said axis is greater than the angle of another of said passages to said axis.

4. A sprinkler head according to claim 1, in which the lower skirt portion of said lower cylindrical member has an annular recess to receive an elastic washer between 15 said neck portion and said lower skirt portion.

5. A sprinkler head according to claim 1, in which there are a plurality of small holes in the end wall of the upper member.

20 6. A sprinkler head according to claim 1, in which said members are substantially cylindrical and of the same external diameter.

7. A sprinkler head comprising a shaft of uniform diameter threaded uniformly throughout its length, said shaft being fluted throughout its length with deep channels 25 extending longitudinally the full length of the shaft, a plurality of substantially cylindrical independently-rotatable, cup-shaped members screwed onto said shaft and spaced apart thereon, each of said members having an annular skirt portion surrounding and spaced from said shaft, the edges of said skirt portions being beveled and the facing peripheral edges of the adjacent members being correspondingly beveled, and a cap screwed on one end of the shaft and spaced from the adjacent one of said members.

30 8. A sprinkler head according to claim 7, in which the cap has a plurality of small holes in the top thereof.

9. A sprinkler head according to claim 7, in which the shaft is substantially cross-shaped in cross section.

10. A sprinkler head comprising a shaft of uniform diameter threaded uniformly throughout its length, said shaft being fluted throughout its length with deep channels 35 extending longitudinally the full length of the shaft and a plurality of internally threaded hollow cylindrical and independently rotatable members screwed onto said shaft and spaced apart from one another, one of said members at one end of the shaft being cup-shaped and forming a cap and one of said members at the opposite end of the shaft having means for connecting it to a fluid supply conduit.

40 11. A sprinkler head according to claim 10, in which the cross sectional area of said channels is approximately equal to the cross sectional area of the solid portion of said shaft.

12. A sprinkler head according to claim 10, in which said channels are trough-shaped with rounded bottoms and have a depth greater than half the radius of the shaft.

45 50 13. A sprinkler head comprising a shaft of uniform diameter threaded uniformly throughout its length, said shaft being fluted throughout its length with deep channels extending longitudinally the full length of the shaft and a plurality of internally threaded hollow cylindrical and independently rotatable members screwed onto said shaft and spaced apart from one another, one of said members at one end of the shaft being cup-shaped and forming a cap and one of said members at the opposite end of the shaft having means for connecting it to a fluid supply conduit.

55 14. A sprinkler head according to claim 10, in which the cross sectional area of said channels is approximately equal to the cross sectional area of the solid portion of said shaft.

15. A sprinkler head according to claim 10, in which said channels are trough-shaped with rounded bottoms and have a depth greater than half the radius of the shaft.

60 16. A sprinkler head according to claim 10, in which the cross sectional area of said channels is approximately equal to the cross sectional area of the solid portion of said shaft.

17. A sprinkler head according to claim 10, in which said channels are trough-shaped with rounded bottoms and have a depth greater than half the radius of the shaft.
